UNITED STATES PATENT OFFICE.

JOHN G. SHUSTER, OF CALDWELL, KANSAS.

RAILWAY-TIE.

SPECIFICATION forming part of Letters Patent No. 753,171, dated February 23, 1904.

Application filed July 11, 1903. Serial No. 165,151. (No model.)

To all whom it may concern:

Be it known that I, JOHN G. SHUSTER, a citizen of the United States, residing at Caldwell, in the county of Sumner and State of Kansas, have invented new and useful Improvements 5 in Railway-Ties, of which the following is a specification.

My invention relates to new and useful improvements in railway-ties; and its object is to 10 provide a device of this character which can also be employed for fastening together the adjoining ends of the rails, whereby a firm connection between the rails may be formed and the ends thereof supported to prevent 15 pounding by wheels passing thereover.

With the above and other objects in view the invention consists in providing a tie, preferably formed of metal, having grooves in the ends thereof for the reception of the base- 20 flanges of the rails and the lower portion of the webs thereof. The flanges extend upward from the sides of these grooves to form fish-plates, which are adapted to clamp upon opposite sides of the webs of the ends of the rails, 25 and thereby securely hold the ends together.

The invention also consists in the further novel construction and combination of parts hereinafter more fully described and claimed, and illustrated in the accompanying drawings, 30 showing the preferred form of my invention, and in which—

Figure 1 is a perspective view of the tie, showing rails in position thereon. Fig. 2 is a plan view of the tie, and Fig. 3 is a front elevation thereof.

Referring to the figures by numerals of reference, 1 is a tie, preferably formed of metal and rectangular in form, the central portion thereof being cut away, as shown at 2, to save 40 material. The ends are also cut away midway their length, whereby is formed a tie of two parallel members connected by two transverse parallel webs. Parallel grooves 3 are formed near the ends of the tie and extend entirely 45 across the width and length of the members and webs, respectively, and below the upper surface thereof and are enlarged at their bases, so as to receive the base-flanges of rails 4. The walls of the remaining portion of the

grooves are parallel. Flanges 5 extend upward from the edges of the grooves 3 and are of such size as to abut against the lower surfaces of the heads of the rails and are spaced apart a sufficient distance to permit the webs of the rails to fit snugly therebetween. 50

When it is desired to secure rails together by means of the tie herein described, the ends of said rails are inserted longitudinally within the grooves 3, so as to bring their abutting ends into position adjacent the center of the 60 slots. Bolts 6 are then inserted through apertures formed within the flanges 5 and through apertures provided therefor in the webs of the rails 4, and the flanges are thus firmly clamped upon the webs of the rails and 65 secure said rails together against independent longitudinal and lateral movement. As the tie is formed in a single casting, it will firmly support the ends of the rails thereon, and as the flanges 5 are integral with the tie it is ob- 70 vious that independent longitudinal movement of the rails is prevented. As the grooves are formed in this invention the tie proper not only receives the base of the rail, but a portion of the web, thereby greatly reducing the 75 strain upon the flanges of the grooves, preventing fracture of the same.

In the foregoing description I have shown the preferred form of my invention; but I do not limit myself thereto, as I am aware that 80 modifications may be made therein without departing from the spirit or sacrificing any of the advantages thereof, and I therefore reserve the right to make such changes as fairly fall within the scope of my invention. 85

Having thus described the invention, what is claimed as new is—

A combined tie and rail-joint comprising a casting having a central cut-out portion and also having its ends cut away to provide two 90 parallel members connected to each other by parallel transversely - arranged webs, said members and webs being provided with grooves extending throughout their entire width and length respectively, and below the 95 upper faces of the members and webs, the lower portions of the grooves conforming to the contour of the flanges of rails and the walls

of the upper portion thereof being parallel, and parallel flanges extending upward from the upper edges of said grooves and extending the entire length thereof, said flanges forming fish-
5 plates and provided with apertures for the re-ception of rail engaging and securing means, the entire device being formed integral.

In testimony whereof I affix my signature in presence of two witnesses.

JOHN G. SHUSTER.
